UNITED STATES PATENT OFFICE

ROBERT GOULD JENNINGS, OF ELMIRA, NEW YORK, ASSIGNOR TO THE R. G. JENNINGS YARN CLEANING MACHINE CO. INC., OF ELMIRA, NEW YORK, A CORPORATION OF NEW YORK

TEXTILE FABRIC

Application filed October 29, 1928. Serial No. 144,928.

This invention relates to improvements in textile fabrics, and more particularly in some of its aspects, to improvements in knit fabrics such as are ordinarily produced by circular or other knitting machines.

It is the general object of the invention to provide a superior knit fabric of increased strength and wearing qualities and having a unique decorative effect.

10 A further object is to provide a fabric of the class mentioned which is provided, in addition to the thread forming the fabric, with one or a plurality of additional textile threads so interwoven and entwined with the 15 stitches of the fabric as to strengthen said fabric and improve its wearing qualities, and also to impart thereto a unique and pleasing decorative effect.

20 Still another object of the invention is to so superpose upon a knit fabric, and to entwine with the wales of the fabric, certain threads in addition to the fabric threads so as to provide distinct stripes and like decorative effects running longitudinally of the 25 fabric.

Other objects will be in part pointed out in the following detailed description of certain illustrative but preferred embodiments of the invention, and will be in part obvious 30 in connection with said description.

The invention accordingly comprises a product possessing the features, properties, and the relation of components which will be exemplified in the product hereinafter described and the scope of the application of which will be indicated in the claims.

35 For a more complete understanding of the nature and objects of the invention, reference is had to the following detailed description, and to the accompanying drawings, in which—

Fig. 1 is a front elevation of a fragment of fabric embodying the invention and showing diagrammatically the general improved decorative effect.

40 Fig. 2 is a front elevation of a fragment of fabric embodying the invention, the threads being shown as magnified and the 45 stitches pulled apart both longitudinally and

transversely in order to clearly disclose the stitch structure.

Fig. 3 is a front view similar to Fig. 1 but showing a variation of the decorative stitch.

Fig. 4 is a view similar to that of Fig. 2, 55 but showing another variation of the decorative stitch structure, and

Fig. 5 is a front elevation similar to Figs. 1 and 3 depicting another variation of the improved decorative arrangement. 60

Referring to the drawing for a detailed description of the illustrative embodiments of the invention there shown, and, first, to the embodiment illustrated in Figs. 1 and 2, it will be observed particularly from Fig. 2 65 that a rib knit fabric A of ordinary construction has a series of inter-looped longitudinally disposed stitches forming the front or outside wales indicated generally at B, the successive transversely disposed outer wales being designated by B', B'', B''' etc. There is also a corresponding longitudinal series of inter-looped stitches forming the rear or inside wale indicated generally at C, the successive transversely disposed inner wales being 70 designated as C', C'', C''' etc. The stitches are arranged in transverse courses indicated generally at D, and the successive longitudinally positioned courses are indicated at D', D'', etc. The stitches are inter-looped 75 with each other both longitudinally and transversely in a manner common to this class of textile fabrics, as will be understood by those skilled in the art. It will be understood that in Fig. 2 the stitches are shown as 80 being stretched apart both longitudinally and transversely for the purpose of clearly disclosing the structure.

As clearly shown in Fig. 2, it will be seen that a thread E, in addition to the threads 85 forming the regular fabric stitches, is inter-twined in the form of a bight with the stitches of the wale B'' of the fabric. There may be as many of these decorative threads 90 E as desired and they may be spaced apart or arranged in spaced groups as preferred to impart the desired fabric reinforcement 95 and decorative appearance, but only one such thread is shown in order to simplify the disclosure and to show the structure clearly. 100

This decorative thread may be laid in position by hand or in any desired manner, a convenient, economical and satisfactory method being disclosed in applicant's copending application, Serial No. 144,672, filed October 28, 1926. The decorative thread may be of a color to contrast with the fabric thread so as to emphasize and enhance the ornamentation.

According to the embodiment of Fig. 2, the additional or decorative thread E is arranged in a series of successive reversely arranged turns forming loops or stitches E', disposed at the right side of the supporting wale B² with the loops thereof facing toward the left, while the reversely disposed loops or stitches E² are disposed at the left of the same wale and opening or facing toward the right. The transversely disposed stretches or lengths E³ of the thread E connect with the adjacent reversely disposed loops E' and E², preferably lying beneath the two longitudinal fabric threads, forming the outer stitch loop of the outer wale B² and lying above the two adjacent inner fabric threads forming parts, respectively, of the two adjacent stitches which form parts of the inner wales lying at either side of the outer wale B². It will thus be seen that the decorative thread E is entwined or inter-looped with the threads of the wale B² so as to be supported by the latter, and furthermore that the outer parts or ends of the loops or stitches E' and E² lie slightly beyond the respective outer sides of the wale so as to be somewhat exposed to view. The transverse strand E³ of the thread E may also be slightly exposed on the outer face of the fabric between the two adjacent strands of the stitch loop of the wale B².

The result of entwining the decorative thread E as described is to lend a unique decorative appearance to the fabric as well as to strengthen and reinforce it and to increase its resistance to wear. It is to be observed that the decorative figure imparted by the decorative threads may be varied by changing the spacing or grouping of these threads, or by varying their color in contrast with each other and in contrast with the color of the fabric itself. Thus varying forms of stripes may be applied to the fabric.

In the diagrammatic representation of Fig. 1 the general appearance of a fragment of fabric A is depicted, there being a longitudinal stripe formed by three decorative threads laid in adjacent outer ribs or wales B of the fabric. In this view the outer wales are designated B and the inner wales are designated C, while the transverse stitch courses of the fabric are designated D. Each individual stripe formed by the respective decorative threads is represented by the relatively heavy staggered short lines, disposed at opposite sides of wales B design-

nated generally by reference F. The dots between respective adjacent ends of the staggered lines represent the horizontal strands E³ of the decorative thread, which may show slightly between threads of the outer stitch loop, as mentioned. It will be understood that the exposed parts of the decorative threads will be revealed to view in varying degrees dependent upon many factors, such as the character of both the fabric and decorative threads, the relative tension of the fabric and decorative threads, the contrasting colors, etc. It will thus be possible to vary the decorative effect over quite a wide range, even in the form of decorative stitch above disclosed.

The ornamentation may be still further varied and enhanced by changing the form of stitch of the decorative thread, as suggested in Fig. 4. This view depicts a fragment of fabric A in a manner similar to that of Fig. 2, and the corresponding elements of the fabric are designated by the same reference characters. The decorative thread E is entwined and supported by one of the external wales, as wale B², but in this case the loops or stitches E⁴ disposed at the right of the wale, are relatively short extending, in the embodiment shown, over a length of one stitch as in Fig. 2, while the reversely disposed loops or stitches E⁵ at the left side of the same wale, are comparatively long, extending over the length of a plurality of successive fabric stitches. These long stitches may span two, three, four, or more successive stitches or courses. As shown, the long decorative stitch E⁵ may and preferably does thus bulge laterally away from the side of the wale B², forming a balloon effect or balloon stitch, which is effective in emphasizing the stripe and enhancing the decorative appearance of the fabric.

In a fabric wherein the balloon stitch is employed the principal decorative effect is imparted by the balloon stitches, due to the relatively greater extent of exposed thread thereof and to its position away from contact with or partial concealment by the wale. The loop E⁴ is relatively inconspicuous in comparison with the balloon stitch. The decorative stitches including both the long and the short stitches may be applied to the fabric by hand or in a manner as described in said copending application, when the fabric A is tensioned longitudinally so as to cause stretching thereof, while the decorative thread is applied at a less tension. The result of this is that the ballooning of the long stitches E⁵ is caused or increased by a greater degree of longitudinal shrinkage of the fabric when the tension thereon is released.

A fragment of fabric A is shown in front elevation in Fig. 5, depicting diagrammatically, as above described in connection with

Fig. 1, the general appearance of a fabric having a plurality of rows of balloon stitches E^5 , each of which spans three adjacent stitch courses D of the fabric. The stripe effect is also shown as being varied by the grouping and spacing of the longitudinal rows of stitches.

A different arrangement of balloon stitch is indicated in Fig. 3, which is a diagrammatic representation similar to Figs. 1 and 5, of a fragment of fabric A. It will be noted that in the other embodiments of the invention, each of the decorative threads E is entwined throughout its extent with the same fabric wale. In Fig. 3, however, the decorative thread E is shifted or transposed from one wale to another. As shown, this thread, for example, that shown on the right in Fig. 3 is first entwined with the wale designated B' at E^4 , forming the balloon loop E^5 attached to the left side thereof. Proceeding from the top of the figure downwardly this same thread is next transposed to the left across the inner wale C^2 , and then entwined with the next adjacent outer wale B^2 to the left to form a balloon stitch E^6 protruding from the left side thereof and attached thereto. The next transposition is made to the right so the next successive stitch E^5 is attached to the wale B' as before, and so on. Each of the other threads forming the decorative stitches may be similarly transposed and attached to the respective wales, the result being that the fabric is provided with a plurality of stripes extending generally longitudinally but deviating from a straight line to form a zigzag or grapevine stripe. It is clear also that the grouping and spacing of this form may be varied, as mentioned in connection with Fig. 5. Also it will be clear that the invention may be applied to other character of fabric, such as the flat knit fabric, as distinguished from the ribbed fabric shown.

Since certain changes may be made in the above product and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. A rib knit fabric having a non-knitted yarn intertwined in the fabric in the form of a bight, a portion of said bight extending coursewise and between the legs of a loop of

a face wale and the legs of loops of adjacent wales.

2. A rib knit fabric having a non-knitted yarn intertwined in the fabric in the form of a bight, the two leg portions of said bight extending coursewise and between the legs of a loop of a face wale and the legs of loops of adjacent wales. 70

3. A rib knitted fabric having a non-knitted ornamental auxiliary yarn intertwined in the fabric in the form of a bight, said bight extending coursewise and between the legs of a loop of a face wale and the legs of loops of adjacent wales. 75

In testimony whereof I affix my signature. 80
ROBERT GOULD JENNINGS.
